UNITED STATES PATENT OFFICE.

ALBERT G. KOUNTZ, OF MOUNT OLIVER, PENNSYLVANIA.

ATTACHMENT FOR TELEPHONES.

No. 825,184.

Specification of Letters Patent.

Patented July 3, 1906.

Application filed January 22, 1906. Serial No. 297,233.

To all whom it may concern:

Be it known that I, ALBERT G. KOUNTZ, a citizen of the United States of America, residing at Mount Oliver, in the county of Allegheny and State of Pennsylvania, have invented certain new and useful Improvements in Attachments for Telephones, of which the following is a specification, reference being had therein to the accompanying drawings.

10 This invention relates to certain new and useful improvements in attachments for telephones; and, the invention has for its primary object the provision of novel means for sounding a continuous alarm when the telephone rings or which may be arranged to sound an alarm simultaneously with the telephone, the duration of the alarm being the same as the telephone.

15 My invention aims to provide an attachment for telephones which may be associated direct with the telephone or may be placed at a considerable distance therefrom to sound an alarm simultaneous with the telephone and notify persons that a call has been made 20 over the telephone. In this connection my invention is particularly adapted for warehouses, factories, and large buildings where the occupants are oftentimes a considerable distance away from the telephone, consequently not being able to hear the same when the telephone-bell rings.

25 To this end I have devised an attachment comprising a small and inexpensive mechanism which is located upon a telephone, and in conjunction with the mechanism I employ a battery and an electric bell which are connected with the mechanism whereby when the same is actuated the electric bell will be sounded until the telephone-call is answered or may be made to sound an alarm of the same duration as the telephone-call.

30 The detail construction entering into my invention will be hereinafter more fully described, and specifically pointed out in the claims, and, referring to the drawings accompanying this application, like numerals of reference designate corresponding parts throughout the several views, in which—

35 Figure 1 is a fragmentary front elevation of a telephone equipped with my improved attachment; and Fig. 2 is a front elevation of the attachment, the front plate or casing thereof being removed to illustrate the mechanism thereof. Fig. 3 is a longitudinal sectional view of the insulating-plate and retaining-strap of the connecting-rod.

In the accompanying drawings I have illustrated a portion of the conventional form of telephone 1 as having a battery-box 2 and alarm-bells 3, which are sounded by a common tapper 4. My invention resides in providing the battery-box 2 adjacent to the bells 3 with a depending shield or plate 5, upon which is pivotally mounted a connecting-rod 6, said rod being retained in engagement with the plate or shield 5 by a screw 7, the connecting-rod being loosely mounted on the screw and free to move thereon for a short distance in the direction of the length of the screw. Directly above the screw 7 I provide the 70 plate or shield 5 with a notched retaining-strap 8, which is adapted to normally hold the connecting-rod in a fixed position centrally of the plate or shield 5 when the connecting-rod is pressed back against the retaining-strap. Upon the insulation-plate 5, at opposite sides of the depending end 9 of the connecting-rod, I mount angular lugs 10 75 and 11, which carry adjusting-screws 11 and 12. The ends of the screws 11 and 12 are connected to the depending end 9 of the connecting-rod by coiled springs 14 and 15.

80 The plate or shield 5 adjacent to the lower end of the connecting-rod 6 is provided with a U-shaped plate or strap 16, carrying screws 17 and 18. The plate or strap 16 is connected by a wire 19 with a conventional form of electric bell 20, said bell being connected by a wire 21 with a battery 22, which in turn is connected by a wire 23 with the pivot-screws 90 7 of the connecting-rod 6.

85 The mechanism carried by the plate or shield 5 is protected by a casing 24, said casing being secured upon the plate or shield 5 by screws 25, thus making the mechanism 95 dust-proof and preventing it from being tampered with when used in connection with the telephone.

90 The connecting-rod 6 is provided with a knob or handle 26, whereby the connecting-rod can be easily adjusted to operate the attachment as a continuous alarm or to sound an alarm of the same duration as the telephone-alarm.

100 The attachment is placed upon the battery-box 2, whereby the connecting-rod 6 will rest lightly against the tapper 4 of the telephone. Should it be desired to operate the attachment as a continuous alarm or call, the knob or handle 26 is gripped to position the 105 connecting-rod 6 within the retaining-strap 8, as shown in Fig. 2 of the drawings. The

connecting-rod 6 is held in this position, while the tension of the spring 15 is released by the screw 12 and the tension of the spring 14 increased by adjusting the screw 11. When the telephone is sounded and the tapper 4 vibrates, it strikes the rear edge of the connecting-rod 6 and forces the rod outwardly on the screw 7 and releases it from the retaining-strap 8. The spring 14 moves the depending end 9 of the rod 6 into engagement with the screw 17, which closes the circuit and causes the electric bell 20 to continuously ring until the connecting-rod 6 is returned to its normal position or the battery 22 becomes exhausted. When the attachment is arranged to sound an alarm of the same duration as the telephone, the spring 14 is released and the tension upon the spring 15 increases until the connecting-rod 6 rests lightly against the tapper 4, as shown in Fig. 1. The screws 17 and 18 are then adjusted until the ends of said screws almost touch the depending end 9 of the connecting-rod. Now as the telephone rings the depending end 9 of the connecting-rod 6 will vibrate between the ends of the screws 17 and 18, thus closing the circuit and causing the bell 20 to ring as long as the tapper 4 vibrates.

It will be observed that the attachment is extremely simple in construction and can be easily and quickly manipulated to sound a continuous alarm or an alarm similar to the telephone in connection with which it is used. The battery 22, together with the bell 20, can be located in some remote part of the building a considerable distance away from the telephone, whereby should the telephone ring persons in the vicinity of the bell 20 will be notified that a call is being made upon the telephone.

I preferably construct the shield or plate of a non-fusible and non-conductive material, while the mechanism carried by said

plate or shield is made of strong and durable metal which will withstand the current of 45 electricity to which it is subjected.

Such changes in the construction and operation of my improved attachment as are permissible by the appended claims may be resorted to without departing from the spirit and scope of the invention.

What I claim, and desire to secure by Letters Patent, is—

1. In a telephone attachment, the combination with the bell-tapper of the telephone, a battery, an electric bell in circuit with said battery, of a non-conductive plate mounted adjacent to the said tapper, a connecting-rod pivotedly mounted upon said plate and adapted to engage said tapper, and in circuit with 55 said battery, a contact-strap carried by said plate and in circuit with said bell, adjustable springs secured to said connecting-rod, means to normally hold said connecting-rod in a fixed position, substantially as described. 65

2. In a telephone attachment, the combination with the bell-tapper of the telephone, of a battery, an electric bell, a connecting-rod mounted adjacent to the said tapper, and in circuit with said battery and said bell, means 70 to normally hold said connecting-rod in a fixed position, means to hold said connecting-rod to complete a circuit through said battery and said bell and continuously sound said bell, means whereby when said connecting-rod is actuated by said tapper, a circuit 75 will be completed of the same duration as the operation of said tapper, substantially as described.

In testimony whereof I affix my signature 80 in the presence of two witnesses:

ALBERT G. KOUNTZ.

Witnesses:

C. KLOSTERMANN,
THOMAS H. SANKEY.
